UNITED STATES PATENT OFFICE

2,261,980

HOSPITALIZATION BED

Charles Drexler and Ralph H. Morgan, Indianapolis, Ind., assignors to Robert R. Freund, Evansville, Ind.

Application July 9, 1937, Serial No. 152,718

5 Claims. (Cl. 5—90)

This invention relates to a posture and hospital bed.

The chief object of this invention is to provide a bed of articulated character, whereby the same may have its several parts moved into various positions necessitated by the patient's particular condition.

Another object of the invention is to provide a mutually coacting combination bed pan and mattress plug arrangement, whereby either may be associated with an aperture in the bed spring and mattress for the specific purpose desired.

Another object of the invention is to improve the invention basically disclosed in the application of Robert R. Freund, filed December 11, 1936, and bearing Serial No. 115,272, and entitled, "Posture bed structure" abandoned and now substituted by an application Serial No. 264,766 filed March 29, 1939.

The chief feature of the invention consists in embodying in a bed structure of articulated character, the several mechanisms, whereby the bed sections and portions associated therewith may be adjusted, maintained, operated and/or utilized, as necessity or convenience may require.

Reference is had to the before mentioned copending application for a specific description of the advantages of a bed structure embodying the basic characteristics of the present and copending application invention disclosures.

The full nature of the invention will be understood from the accompanying drawings and the following description and claims:

In the drawings

Fig. 1 is a side elevation of a bed structure of the central supported or pedestal type, embodying the invention, parts being broken away to illustrate the other parts in detail, said figure illustrating the respective mechanisms for moving the respective sections of the articulated bed and sustaining the same in moved position.

Fig. 2 is a transverse sectional view of, more especially, the power mechanism, other parts, however, being shown in elevation.

Fig. 3 is a longitudinal sectional view of the bed pan and mattress plug embodiment of the invention.

Fig. 4 is a transverse sectional view taken on line 4—4 of Fig. 3 and in the direction of the arrows.

Fig. 5 is a transverse sectional view taken on line 5—5 of Fig. 1 and in the direction of the arrows.

Fig. 6 is a top plan view of the bed structure 55

embodimenting the invention, the plug portion being omitted for clearness.

In Figs. 1 and 6 there is illustrated a pair of side frame members 103 having reenforcing webs 103a, if desired, and each lower corner of the frame member terminates in a socket 104 to receive the upper end 105 of an offset or angular leg 106, terminating in a caster socket 107 mounting a caster 108. It will be noted from a comparison of Figs. 1 and 3 that the two frame members are slightly dissimilar in their central portions and the same are connected together by the cross member 110. The two frame members are connected at their upper portion as indicated at 110a and 110b, connection 110a having solely a connecting function, while 110b has an additional function hereinafter to be pointed out.

Portion 100 of each side frame pivotally supports at 10 an arm or frame extension 102 and the free ends thereof are united as at 11. Member 11 is of channel shape in cross section and substantially U-shaped, and the ends thereof are secured to the members 102, as indicated at 11a in Fig. 3.

One of the members 102 includes a depending lever arm extension 12 which terminates in a cable anchorage 13 to which is connected one end of the cable 14, the same passing over a pulley 15 rotatably supported on the axle 16 carried by the yoke 17, the stem 18 of which is suitably secured in a socket 19 formed in the frame member 103 shown in Fig. 1. The other end of the cable 14—see Fig. 2—is secured to a winding drum 20, the support and rotational power therefor being hereinafter set forth more in detail.

Each member 101 is pivotally supported at 21 on portions 100 of the side frame member 103 and the members 101 each support a channel member 22 at one end, the other end of the member 22 being secured to a hinge member 23a provided with a hinge pin 24 that supports the complementary hinge member 23b. The hinge members 23a are maintained in spaced relation through the connection of members 101 to the portions 100 maintained in spaced relation as aforesaid. The hinge members 23b are provided with depending ears 25, and a connecting rod 26 maintains the same in spaced relation. A U-shaped channel member 27 is suitably associated with the members 23b and constitutes the end extension of the bed frame.

There is thus provided a bed frame structure which is articulated at 10, 21 and 24, portions 100 representing the fixed or horizontal portion, portion 11 representing the head or back portion

adapted for upward tilting through the instrumentality of the cable 14, section 20 represented by numerals 101, 22 and 23a, adapted for articulation about the axis of members 21 as a pivot, and the section represented by numerals 23b and 27 pivoted on an axis embodying the members 24, which latter axis is movable as determinable by the tilting of the intermediate articulated section. The last mentioned or end section 23b-27 constitutes the foot section.

Pivotedly supported on the transverse connecting member 110b adjacent each member 103 is an arm 28 and each arm at its free end supports a pivot 29, in turn supporting a roller 30 which constitutes a rolling support for the parallel portions 27 of the bed frame. In a similar manner there is pivotally supported at 31 on each of the side frame members 103, an arm 32 supporting a pivot 33 upon which is pivotally mounted the roller 34 for member 22.

The lower web of each of the flanged sections, for example 11, 100, 22 and 27, and the like, is suitably apertured—see Fig. 2—as at 35 and a coil spring 36 has one end 36a mounted therein and its opposite end 36b is mounted in the aperture 37 of a flat spring or strap 38, it being understood that, except for that portion of the bed which corresponds to the portion of the invention illustrated in Figs. 3 and 4, the straps 38 extend from one side of the bed frame to the opposite side and these flat strap springs support the mattress 111, to which reference will be had more fully hereinafter.

There is secured to the frame member 103 a housing structure 39 which provides aligned bearings 40a, 40b and 40c in which is mounted a shaft 41. The lower end of the shaft mounts in the chamber 42 a worm wheel 43 meshing with a worm 44 carried by the motor shaft 45 in the chamber 42. The motor shaft 45 is operable by the motor mechanism embodied in the electric motor which is of the reversible type and which is provided with suitable controls for initiating motor operation in either direction of rotation, such control mechanism being of the normally open type switch in that it requires manual maintenance of the switch in closed position to secure motor energization and release from said manual operation immediately causes cessation of rotational movement, the switch being of dual character such as necessary to secure reverse rotation.

As herein illustrated, the power is derived in the present disclosure, as thus far described, from the reversible motor structure. As shown in Fig. 2, the motor 46 is suitably mounted on the frame structure, which it will be apparent is of the central or pedestal type in that the head and foot frame portions of the bed frame project beyond the support. The central support is of divided or spaced character, being connected, as stated, as at 110, 110a, and 110b, and otherwise connected near the top in conjunction with portions 100 as may be desired or required.

Rotatably mounted on shaft 41 is a gear 47, and if desired, an anti-friction construction 47a may be interposed therebetween. The gear 47 bears at its lower end on a thrust bearing arrangement 48 in turn bearing on the shaft bearing 40c. The gear 47 has a toothed clutch face 49 and nests an anti-friction construction 50 which supports a sleeve 51 keyed to the shaft 41.

Bearing on the upper end of sleeve 51 is an anti-friction structure 52 against which bears another gear 53 of toothed character similar to gear 47 and similarly mounted as at 53a on said

shaft 41 but in reversed relation is clutch face 54 so that in this instance the clutch face 54 is positioned adjacent but spaced from the clutch face 49. Thus, the two gears are maintained in spaced relation and are prevented from axial movement by the inclusion of a thrust bearing structure 55 between the gear 53 and the bearing 40b.

A clutch member 56 has the opposite clutch faces with teeth 56a and 56b either of which is adapted for engagement with the teeth 49 or 54, respectively, of the gears 47 and 53. The clutch member 56 is of a length sufficient to, as stated, engage either of the gears, or, as illustrated, to be positioned intermediate the same and be free from gear tooth face engagement. The clutch member 56 has a spline or equivalent connection with the sleeve 51, so as to be capable of longitudinal movement relative thereto but incapable of relative rotational movement, so that said clutch member rotates with the shaft 41 and in the direction of shaft rotation. Each gear 47 or 53, therefore, may be disconnected from the source of power or may be connected thereto and rotated in either direction, as will be more fully pointed out hereinafter.

Positioned above the bearing 40b is a thrust bearing structure 57 and another gear 58 is rotatably supported on the shaft as at 59 and is provided with a clutch face having teeth 60. The anti-friction structure 61 nested therein serves as a spacer for the sleeve 62 rigidly secured to the shaft 41 and the thrust bearing 63 maintains the gear 64 in predetermined position, the latter being rotatably supported as at 65 on the shaft 41. The gears 58 and 64 have the adjacent clutch faces with teeth 58a and 64a, respectively, and the clutch member 66 has the clutch faces with teeth 66a and 66b at opposite ends for selective engagement with the clutch faces before mentioned. The clutch member 66 has a splined or equivalent connection with the bushing or sleeve 62 similar to that previously described with reference to the clutch member 56 with its supporting and driving sleeve 51. Fig. 1 illustrates the neutral position of the clutch member 66.

To prevent endwise play and maintain predetermined clearances and positionings, there is interposed between the gear 64 and the bearing 40a the thrust bearing structure 67. Pinned to the upper free end of the shaft 41 as at 68a is a power cam 68 having the cam groove 68b therein and a follower 69 rides in said groove and is carried by the rocker arm 70 pivoted at 71. The rocker arm is apertured as at 71a for the purpose hereinafter set forth and adjacent said aperture is pivotally connected as at 71b, to the connecting rod 72 in turn connected to a piston 73 slidably mounted in the pump cylinder 74 which is provided with an intake port 75, the latter being connected by the conduit 76 to the chamber 42 and terminating at 76a in the lowermost portion thereof. The discharge port and its connection to the discharge line 77 is not illustrated herein.

The discharge line 77 terminates at 77a adjacent the bearing 40a and thus in the rotation of shaft 41 the rocker arm is continuously actuated and the lubrication pump similarly actuated to supply lubricant to the power mechanism previously described, and mounted upon the shaft 41.

The means for selectively controlling the several clutch constructions may be set forth brief-

ly as follows: A shaft 80 is rotatably supported in a bearing 80a formed as a part of the pump housing. Pinned thereto at 80b and bearing on the end of the bearing 80a is a grooved cam 81 having the cam groove 81a therein. A clutch shifter lever 82 is pivotally supported at 83 and is yieldingly locked by a plunger 84 and spring 84a to an arm 85 pivotally supporting the roller 82a which is positioned in the groove 81a. The lever 82 is bifurcated and each arm pivotally supports at 86 a roller 86a which rides in the groove 87 of the clutch member 56, splined as at 51a to the sleeve 51, pinned to the shaft 41 as at 51b.

It will be obvious from the shape of the cam 81 that the clutch shifter lever structure may be moved so as to position the clutch in neutral position or in either selective gear driving position.

In a similar manner, there is suitably secured to the shaft 80, a grooved cam 88 with which is associated a similar type lever structure 89 pivoted at 89a and operatively associated with the groove 90 in the clutch member 66.

As appears in Fig. 1, cams 81 and 88 are mounted on shaft 80 in angular offset relation as well as axial offset relation. These cams are identical. When handwheel 93b (see line 37, below) is turned angularly, the proper amount, clutch members 56 and 66 may be raised or lowered or positioned therebetween or in neutral position.

The shaft 80 has pinned thereto a collar 91 which maintains the shaft against axial displacement. The free end of the shaft 80 supports a transverse pin 92 which is adapted to be interlocked with a toothed socket structure 93 having the teeth 93a thereon and having a handle portion 93b, and a pointer or indicator portion 93c. The portion 93 is rotatably supported in the opening 94 formed in the cover portion 95 of housing 39 which is the housing for all of the aforesaid power mechanism. 95a indicates a scale or like legending so that by manual manipulation of the member 93b all the gears may be free from rotation or any one of the gears may be rotated and, of course, the direction of rotation depends upon the direction of rotation of the motor before mentioned.

In place of motor operation, there may be associated with the upper end of the shaft 41, a cap type socket 96 having a cooperative engagement with the upper end of the shaft 41 and provided with a handle 97 terminating in a knob 98. The member 96 is rotatably supported in the aperture 96a formed in the cover 95. When the motor is not employed, it will, of course, be evident that shaft 41 may be manually rotated, through the handle structure described, in either direction and the proper power operation obtained therefrom, depending upon the setting of the manual member 93.

Reference will now be had more especially to Fig. 2 and also to a limited extent to Fig. 1. Rotatably supported in the bearing 160 is a shaft 161 which is connected by a universal coupling 128 to a shaft 122 for rotating said shaft in either direction and for operating the bed pan and plug supporting mechanism, as hereinafter set forth and for the purpose similarly set forth. The shaft 161 has secured to it, in the chamber formed by the housing 39, the gear 162 which is in continuous mesh with the gear 47. In a bearing 163 thereabove is rotatably mounted a shaft 164 to which is secured for bed part movement the drum 20 as at 165 and within the chamber formed by housing 39 there is secured to shaft

164, the gear 166 which is in continuous mesh with the gear 53.

In a bearing 167 thereabove, see Fig. 2, is rotatably supported a shaft 168 which has rigidly secured to it in the chamber formed by the housing 39, a gear 169 and in continuous mesh with the gear 53. The other end of the shaft 168 has rigidly secured to it a lever arm 170 for bed part movement to which reference will be had hereinafter and more especially foot section 27 through arm 183, rockshaft 110b, lever 28 and roller 30 riding thereunder.

In a bearing 171a thereabove is rotatably supported a shaft 171 which has rigidly secured to it in the chamber formed by housing 39 a gear 172 which is in continuous mesh with the gear 64. The other end of the shaft 171 has pinned or otherwise rigidly secured to it, an offset lever 173 for bed part movement to which reference will be had hereinafter and more especially knee section 22 through lever 32 and roller 33 riding thereunder.

Lever 12 connected at one end to the cable 14—see Fig. 1—as before set forth, is rigid with one of the bed frame portions to-wit fixed portion 11, 102, pivoted at 10. Each frame member 103 supports a cam forming structure 174, see Figs. 1 and 3, having the straight portion 175, see Fig. 1, and the arcuate portion 176, see Fig. 1. These cam structures are directed inwardly towards each other. Also rigid with each side of the head portion 11—102 of the bed structure and depending therefrom adjacent each cam structure, is an arm 177, see Fig. 1 pivotally supporting a roller 178 that rides on said cam portions 175—176, of cam member 174 so that during a certain portion of the movement of the drum 15 the tilting of the head portion 11—102 of the bed frame structure is more rapidly effected than at another portion of the movement of the drum, or no tilting is effected for drum movement. This is because the shape or cam surface 175—176 varies.

It will be recalled that lever 32 is operatively associated with the intermediate articulated bed section and is pivoted at 31 in the boss 180 which is an extension of or is an attachment to the power supporting frame member 103. The opposite end of the lever 32 is connected to a link 179 and the other end of link 179 is connected to the arm 173 secured, as before stated, to the shaft 171. The shaft 171 is rotatably supported in the sleeve 170—182 mounted in the bearing 171a and said bearing is suitably supported as at 182—see Fig. 2—to insure rigidity and alignment of the parts, said bearing 182 being rigid with a power supporting frame member 103 to which housing 39 is secured.

The lever 28 associated with the foot section of the articulated bed is rigid with the lever arm 183 pivoted as at 184 to a link 185, the other end thereof being pivoted as at 186 to the lever arm 170, before mentioned. It will be noted that levers 173 and 32 by the link connection 179 constitute a parallel arrangement and that levers 183 and 170 connected by the link 185 constitute a parallel arrangement. Thus, single power connection may be applied to the pivot portions 31 and 110b for actuating the two pairs of aligned levers 32 and 28, respectively. Only a single drum also is required in view of the dual employment of the cam and follower structures 175—176 and 178.

There may be embodied in the aforesaid bed structure, the following bed pan arrangement. The two side members of the frame are desig-

nated by the numeral 103, and the upper portions thereof are designated by numeral 100, the numerals 101 and 102 designate the extensions thereof, 103 the side bracket depending from portion 100 and terminating in the lower corners in leg sockets 104 that receive the portion 105 of the angular leg 106 terminating in the caster socket 107 mounting the caster 108.

The two frame members 103 include between the two leg sockets 104 the depending portions 109 united by the cross member 110. This forms the pedestal, as it were, of the bed structure. The frame structure generally indicated by the numerals 100, 101 and 102, support a spring structure which in turn supports the mattress 111 having the opening 112 therein. A mattress plug 113 is adapted to fill this opening and complete the mattress in normal relationship.

When a bed pan is required and the patient cannot be moved or it is preferable not to move the patient, the plug is removed from the opening 112 and a bed pan is positioned therebeneath.

The instant portion of the invention is directed to the bed pan support and the plug support and the means for securing conjoint movement thereof for positioning one or the other in registration with the opening 112 in the mattress for the respective purpose desired.

The bed pan is indicated by the numeral 114 and includes an inwardly directed lip 114a which drains inwardly to the pan. It is supported by a base 115 apertured at 115a to reduce the weight thereof. A pair of ears at opposite sides of the support or base is provided and in Figs. 3 and 4 numeral 116 indicates the same. Depending therefrom and in slightly offset relation, as shown clearly in Fig. 3, is another ear 117. A link 118 is pivoted at one end to the ear 116 by means of the pin 119 and its opposite end is pivoted as at 120 to one arm of a lever member 121, in turn rigid with the shaft 122.

Shaft 122 is rotatably supported in the bearing 123 which is formed near the lower end of the depending arm 124, secured as at 125 to a depending frame member 126 suitably secured as at 127 to the frame member 100. Member 126 is a casting which includes two depending portions, as shown in Fig. 4, and two transverse connecting portions 126a and 126b, as shown in Fig. 3, the same forming a rectangular tubular guide or shield for plug reception and pan protection. The shaft 122 on the outer end may have a suitable connection thereon, as indicated by the numeral 128, for manual or power rotation of the shaft, as before set forth.

Depending from the depending arm with respect to the bearing 123, is the ear 129 carrying a stud 130 to which is secured one end of the spring 131. The opposite end of the spring 131 is secured by means on the stud 132 to the ear 117. The pan support includes the projecting portion 133 mounting stud 134 to which one end of spring 135 is secured, the other end of the spring 135 being secured to stud 136 mounted in the ear 137 of the depending arm member 124. Simultaneously secured to the member 126 with the arm 124 is a guide structure, comprising the ways 138 and mounted on the member 119—see Fig. 4—is a guide member 139 having the portion 140 which is adapted to ride in said ways.

When the shaft 122 is rotated counterclockwise—see Fig. 3—the pan support by reason of the parallel spring connection and the guide and way association initially, is caused to move directly downwardly and thence after the guide is

free from the ways, the pan support moves toward the left and downwardly into the dotted line position as shown in the lower left hand portion of Fig. 3. This positions the pan in relatively exposed relation so that it is not only readily accessible for removal but may be lifted from the pan support for cleaning purposes.

Reference will now be had to the plug structure and its support. Plug 113 is rigidly but suitably secured to a base 141 and the latter at each side is provided with an ear 142 mounting a stud 143 which pivotally supports one end of a lever 144, the other end being pivotally connected as at 145 to the opposite end of the lever arm 121. It is noted the lever 121 has its two arms slightly biased relative to each other.

Suitably secured to the base portion 141 is a central stem member 146 which is relatively elongated and includes therein an elongated slot 147 and the shaft 122 is mounted in said slot. The stud 143 supports one end of the spring 148, the opposite end being supported by the shaft 122 as at 149. In order to prevent lateral movement of the stem 146 with reference to the shaft 122, adjustable collars may be mounted thereon to retain the stem member 146 in predetermined position on said shaft and yet permit the stem member to move radially relative to the shaft.

In the counterclockwise movement, previously mentioned, as lever arm 121 moves counterclockwise, the stem simultaneously moves therewith and in the continued movement, the stem is elevated by reason of the mutual constraint imposed on the respective parts so that near the end of the movement, the plug is substantially in registration with the opening 112 and final movement positions the plug 113 in the aperture 112 and completes the mattress structure.

To prevent excessive movement, the links 118 are provided with lateral extensions 118a which comprise stops for engaging portions of the levers 121 immediately adjacent thereto, as shown in the lower central portion of Fig. 3 by the dotted lines. Similarly, the links 144 are provided with lateral extensions 144a which comprise stops for engaging portions of the levers 121 immediately adjacent thereto, as shown by the full lines in the lower central portion of Fig. 3.

It will thus be apparent that as the shaft 122 is rotated counterclockwise, the pan is removed and the plug is associated with the opening 112 in the mattress and on clockwise rotation of shaft 122, the plug is removed and the pan is positioned in registration with the opening 112, as shown in the full lines in Fig. 3. If desired, the stud 143 may mount a guide which also may be operatively associated with the ways 138, although the stem 146 and its association with the shaft, normally provides sufficient guidance.

While the invention has been illustrated and described in great detail in the attached drawings and foregoing description, the same is to be considered illustrative and not restrictive in character. Various modifications have been hereinbefore pointed out and these together with others which will readily suggest themselves to persons skilled in this art, are all considered to be within the broad scope of the invention, reference being had to the appended claims.

The invention claimed is:

1. In an invalid bed including a frame structure, a mattress supporting spring structure having an aperture therein and supported by the frame structure, a mattress structure on the

spring structure and having an aperture therethrough registering with the first aperture, and a plug for the mattress aperture, the combination of a bed pan support, a plug support, an aperture defining frame operatively connected to the frame structure and registering with the registering apertures and therebeneath, support moving means reversely operable to alternately remove either support from aperture registration and vice versa, the plug being receivable by the mattress structure aperture and the bed pan support being nestable within the aperture of the second mentioned frame when said supports are at the highest elevation, the supports being operatively connected together and simultaneously movable by the moving means, and guide means depending from a pair of opposite sides of the second mentioned frame, and means carried by each support and operatively engaging said guide means near the end of the elevating movement of the respective support for support guidance and aperture registration.

2. A dual support structure including in combination a frame, a pivotally mounted dual arm lever thereon, a stem having an elongated slot in one end thereof, a member slidable in said slot, a device support carried by the other end of the stem, a link between one lever arm and the device support, yielding means between the device support and the member normally constraining said member towards the device support end of the slot, another device support, a link between the latter device support and the other arm of said lever, and parallel, elongated, substantially equal length yielding means, each stationarily mounted. 35

5 at one end and upon the frame and connected at the opposite end to the second mentioned device support, each of said yielding means being offset linearly to each other and with the lever axis lying therebetween for holding the second mentioned device support horizontal.

10 3. A device as defined by claim 2, characterized by the addition of a stop between each link and the lever arm to which it is connected for limiting rotative movement of the respective link upon the lever arm in one direction and about the pivotal connection therebetween.

15 4. A device as defined by claim 2, characterized by the addition of relatively stationary ways on said frame, and a guide member carried by each of the device supports for selective registration with the ways at one portion of each support movement toward the ways and guide movement therein in another portion of the movement of the last mentioned guide and support.

20 5. A device as defined by claim 2, characterized by the addition of a stop between each link and the lever arm to which it is connected for limiting rotative movement of the respective link upon the lever arm in one direction and about the pivotal connection therebetween, relatively stationary ways on said frame, and a guide member carried by each of the device supports for relative registration with the ways at one portion of each support movement toward the ways and guide movement therein in another portion of the movement of the last mentioned guide and support.

CHARLES DREXLER.
RALPH H. MORGAN.
